UNITED STATES PATENT OFFICE.

EDWARD T. KEENAN, OF BREWSTER, FLORIDA.

VIBRATION MECHANISM FOR SCREENS.

Application filed September 25, 1924. Serial No. 739,789.

The present invention relates to vibration mechanism, and is more particularly directed toward a vibrating screen suitable for sifting ground ore, sand, or other comminuted material.

An object of the invention is to provide an improved electrically responsive mechanism for imparting a vibrating movement to a reciprocating member, which may be come the operator for vibrating other devices.

Another object of the invention is to provide a sifting screen with an improved electromagnetically operated vibratory mechanism for vibrating the screen.

More specifically the invention contemplates the vibration of a sifter screen by a polarized plunger which is vibrated by alternating the direction of an external magnetic field to which the plunger is subjected.

In the accompanying drawings, there is shown, for purposes of illustrating the invention, two of the many possible embodiments of the vibratory mechanism contemplated by the present invention, together with a vibratory screen actuated thereby, it being understood the drawings are merely illustrative of the invention, which may be embodied in various forms.

In these drawings:

Fig. 1 is a side elevation of a screen and vibratory operating mechanism, parts being broken away.

Fig. 2 is an end view, taken from the right of Fig. 1.

Fig. 3 is a section taken on the line 3—3 of Fig. 1, parts being omitted.

Fig. 4 is a detached view showing a screen coupling device; and

Fig. 5 illustrates a modified form of magnet structure.

The vibratory screen may be mounted on any convenient stationary supporting frame. A convenient form of supporting frame may be made from angle iron, as shown in the drawings. This frame has a base made up of a pair of longitudinal angles 10 and 11 connected by cross braces 12. The rear of the supporting frame is made up of a pair of vertical members 13, (only one of which appears in the drawing) and a cross member 14, at the front of the base there are two front vertical members 15 (only one of which appears in the drawing) which are stiffened by a cross

brace 16. The rear cross member 14 supports bearing members 17, which are pivotally supported by similar bearing members 18 carried underneath a screen frame 19. The lower end of the screen frame is carried between the uprights 15, the screen frame and uprights being slotted as shown at 20 and 21, so that the screen frame may be adjustably clamped in position by bolts 22. It is, of course, intended that the screen be provided with suitable chutes for delivering the material to be screened and for carrying for the sifted material and the tailings, but these are omitted from the drawings for purposes of clearness.

The screen frame 19 carries a screen 23 made up of a suitable piece of screen metal 24 and side clamping and shield members 25, 25^a, and 26, 26^a, shown more in detail in Figure 4. Suitable tensioning devices 27 are provided for stretching the screen metal. The above described mounting of the screen on the screen frame is, of course, only one of the many ways in which it may be conveniently mounted.

The screen frame 19 is provided, at about the middle of its length, with transverse members 28 and 29, shown in the form of channels, which may conveniently be carried above the screen frame by means of built up angle iron supports 30 and 31. These transverse members add rigidity to the screen frame and act as supports for the vibratory operating mechanism for agitating the screen.

A transverse shaft 32 is mounted in bearings 33 carried on bearing supports 34 fastened to the transverse members 28 and 29. This shaft is adapted to be power driven in any suitable manner, and is provided with a multipolar magnet structure 35. This structure is provided with exciting windings 36 so as to give the alternate polarity as shown. These windings are preferably connected to a pair of collector rings 37 and 38 carried on the shaft 32, so that the windings may be excited from any suitable source.

The screen 23 is preferably provided with a longitudinal strap 39 bolted underneath the screen metal, and this strap is bolted to the lower end of a plunger 40 of magnetic material. This plunger passes perpendicularly upwardly between the transverse members 28 and 29 and a pole piece 41 it attached to its upper end pref-

erably by a tapered thread and a pin, as shown.

The plunger is preferably energized by a solenoid coil 42 disposed between the channels 28 and 29 so that a strong magnetic pole is produced at the ends of the plunger. The lower end of the plunger is provided with an anvil block 43 adapted to engage an anvil block 44 supported from the transverse frame in any convenient manner, as by a bridge 45. This bridge is provided with a tubular member 46 threaded at its upper end to receive a threaded plug 47. This plug provides a convenient means for controlling the tension in a spring 48 housed inside the tubular member and upper anvil block.

The coil 42 may be energized from any suitable source, and is shown as being placed in parallel with the windings of the rotary magnet structure. It may, however, be connected in series, or one may generate the exciting current directly in the rotating structure, thereby rendering any external connection unnecessary.

The residual magnetism in the plunger, when the coil 42 is disconnected, is in some cases sufficient to cause the vibration, as the plunger is attracted by the rotating magnetic structure, and the weight of the screen and load and the spring forces the screen downward as the influence ceases. There is also in some cases sufficient self-polarization to cause the screen to vibrate when the magnets are rotated.

The shaft 32 is adapted to be rotated at a convenient speed by any suitable source of power, not shown. The rotation of the shaft carries the alternate north and south poles of the magnet structure past the pole piece 41 and thereby subjects it to the influence of the alternation of the magnetic field induced by the rotating magnet structure. The coil 42 polarizes the plunger in a predetermined manner. When the pole of rotating magnet structure is like the pole at the upper end of the plunger the magnetic repulsion forces the plunger downwardly, this movement being, to some extent assisted by the spring 48. When, however, the rotating structure has turned to place the next pole adjacent the pole piece of the plunger, the poles are unlike, and, as such poles attract, the plunger is brought upwardly. The upward movement of the plunger is limited by the engagement of the anvil blocks 43 and 44, thereby preventing the pole 41 from reaching the rotating magnet structure. As rotation of the shaft 32 causes a rapid change in the magnetic field, this results in a rapid vibration of the plunger and whatever is attached to it. In the present case it causes a rapid vibration of the screen and agitates the material in a vigorous fashion. The speed may readily be

controlled, and the device may be operated by either direct or alternating current.

In the modified form of magnet structure shown in Figure 5, the transverse frame members 28' and 29' carry laminated strips 50 and 51 whose upper ends 53 and 54 are adapted to be magnetized by induction from a rotating magnet 52. The lower ends 55 and 56 of the strips 50 and 51 are brought close together thereby providing a better electromagnetic circuit, and the pole piece 41 on the plunger 40 is disposed just below said lower ends 55 and 56. The plunger will be alternately attracted and repelled as before.

It is obvious that the invention may be embodied in many forms and constructions, and I wish it to be understood that the particular forms shown are but a few of the many forms. Various modifications and changes being possible, I do not limit myself in any way with respect thereto.

What is claimed is:

1. In combination, a supporting frame, a screen frame adjustably mounted on the supporting frame, a screen carried from the screen frame, a magnetizable plunger attached to the screen and electromagnetic means for vibrating the plunger, including a rotatable magnet structure bodily carried by the screen frame, said rotatable magnet structure alternately attracting and repelling the plunger.

2. In combination, a supporting frame, a screen frame adjustably mounted on the supporting frame, a screen carried from the screen frame, a magnetizable plunger attached to the screen, screen-frame supported guiding means for the plunger, and electromagnetic means for vibrating the plunger, including a rotatable magnet structure bodily carried by the screen frame, said rotatable magnet structure alternately attracting and repelling the plunger.

3. In combination, a supporting frame, a screen frame adjustably mounted on the supporting frame, a screen carried from the screen frame, a magnetizable plunger attached to the screen and extending upwardly therefrom, electromagnetic means for vibrating the plunger, including a rotatable magnet structure bodily carried by the screen frame, and means for limiting the upward movement of the plunger, said rotatable magnet structure alternately attracting and repelling the plunger.

4. In combination, a supporting frame, a screen frame adjustably mounted on the supporting frame, a screen carried from the screen frame, a magnetizable plunger attached to the screen, a rotatable shaft bodily carried by the screen frame, and electromagnetic means for vibrating the plunger, including a magnet structure carried by the shaft to rotate therewith, said rotatable

magnet structure alternately attracting and repelling the plunger.

5. In combination, a screen frame, a screen carried by the frame, a plunger connected to the screen to vibrate the screen, and means to vibrate the plunger, comprising a stationary solenoid surrounding the plunger to magnetize it, and a rotatable magnet structure disposed adjacent the free end of the plunger to subject the plunger to the influence of the alternation of the magnetic field as the magnet structure is rotated whereby the plunger is vibrated.

15 6. In combination, a screen frame, a screen carried by the frame, a plunger connected to the screen to vibrate the screen, and means to vibrate the plunger, comprising a stationary solenoid surrounding the plunger to magnetize it, and a rotatable magnet structure disposed adjacent the free end of the plunger to subject the plunger to the influence of the alternation of the magnetic field as the magnet structure is rotated whereby the plunger is vibrated, said rotatable magnet structure being supported from the screen frame.

the screen frame.

7. In combination, a screen frame, a screen carried by the frame, a plunger connected to the screen to vibrate the screen, and means to 30 vibrate the plunger, comprising a stationary solenoid surrounding the plunger to magnetize it, a transverse shaft rotatably carried above the screen frame, and a magnet structure carried on the shaft and disposed 35 adjacent the free end of the plunger to subject the plunger to the influence of the alternation of the magnetic field as the magnet structure is rotated whereby the plunger is vibrated.

40 8. In combination, a screen frame, a screen carried by the frame, a plunger connected to the screen to vibrate the screen, and means to vibrate the plunger, comprising a stationary solenoid surrounding the plunger to magnetize it, a transverse shaft rotatably carried above the screen frame, a magnet structure carried on the shaft and disposed adjacent the free end of the plunger to subject the plunger to the influence of the alternation of the magnetic field as the magnet structure is rotated whereby the plunger is vibrated, exciting windings for the magnet structure and collector rings for connecting the windings to an external circuit.

55 9. In combination, a screen frame, a screen carried by the frame, a plunger connected to the screen to vibrate the screen, and means to vibrate the plunger, comprising a stationary solenoid surrounding the plunger to
60 magnetize it, a transverse shaft rotatably carried by the screen frame above the screen, and a magnet structure carried on the shaft and having alternate north and south poles adapted to be brought adjacent the free end
65 of the plunger.

10. In combination, a screen frame, a screen carried by the frame, a plunger connected to the screen to vibrate the screen, and means to vibrate the plunger, comprising a stationary solenoid surrounding the plunger to magnetize it, a transverse shaft rotatably carried by the screen frame above the screen, a magnet structure carried on the shaft and having alternate north and south poles adapted to be brought adjacent the free end of the plunger, exciting windings for the magnet structure and collector rings for connecting the windings to an external circuit. 70 75

11. In combination, a frame, a multipolar magnet structure rotatably supported from the frame, a polarized armature reciprocably carried by said frame in a position to be attracted or repelled by the magnetic field induced by the magnet structure, and a screen connected to the armature to be vibrated thereby.

12. In combination, a frame, a multipolar magnet structure rotatably supported from the frame, a polarized armature reciprocably carried by said frame in a position to be attracted or repelled by the magnetic field induced by the magnet structure, an energizing coil for the armature, and a screen connected to the armature to be vibrated thereby. 90 95

13. In combination, a frame, a shaft rotatably carried on the frame, a multipolar magnet structure having alternate north and south poles and coupled to the shaft, exciting windings for the magnet structure, collector rings for connecting the windings to an external circuit, a polarized armature carried on the frame in a position to be alternately attracted and repelled when the magnet structure is rotated, and a device attached to the free end of the armature to be vibrated thereby. 100 105

14. In combination, a frame, a shaft rotatably carried on the frame, a multipolar magnet structure having alternate north and south poles and coupled to the shaft, exciting windings for the magnet structure, collector rings for connecting the windings to an external circuit, a polarized armature carried on the frame in a position to be alternately attracted and repelled when the magnet structure is rotated, a magnetizing coil for the armature in parallel with the exciting windings, and a device attached to the free end of the armature to be vibrated thereby. 110 115 120

15. In combination, an obliquely disposed screen carried on a frame, a plunger connected to the free part of the screen, and guided for reciprocation perpendicular to the screen, a solenoid coil for magnetizing said plunger so that its free end has a predetermined polarity, a magnet structure rotatably carried adjacent the free end of the 130

plunger and having alternate north and south poles, and means to rotate said structure whereby the plunger is alternately attracted and repelled.

5 16. In combination, an obliquely disposed screen carried on a frame, a plunger connected to the free part of the screen, and guided for reciprocation perpendicular to the screen, a solenoid coil for magnetizing

10 said plunger so that its free end has a predetermined polarity, a magnet structure rotatably carried adjacent the free end of the plunger and having alternate north and south poles, means to rotate said structure

15 whereby the plunger is alternately attracted and repelled, and means to prevent the plunger and magnet structure from coming in contact.

20 17. In combination, a screen, a strap carried underneath the screen, a plunger attached to the strap and extending perpendicularly above the screen, means for guiding the plunger to permit it to reciprocate longitudinally, a solenoid coil surrounding the 25 plunger, a pole piece carried by the free end of the plunger, a movable magnet structure, and means to bring alternate north and south poles adjacent the pole piece whereby the pole piece is alternately attracted and repelled.

30 18. In combination, a screen, a strap carried underneath the screen, a plunger attached to the strap and extending perpendicularly above the screen, means for guiding the plunger to permit it to reciprocate longitudinally, a solenoid coil surrounding the 35 plunger, a pole piece carried by the free end of the plunger, and a rotatable magnet structure disposed adjacent the free end of the plunger to subject the plunger to the influence of the alternation of the magnetic field as the magnet structure is rotated whereby the plunger is vibrated.

40 19. In combination, a screen, a strap car-

ried underneath the screen, a plunger at 45 tached to the strap and extending perpendicularly above the screen, means for guiding the plunger to permit it to reciprocate longitudinally, a solenoid coil surrounding the plunger, a pole piece carried by the free 50 end of the plunger, and a rotatable magnet structure disposed adjacent the free end of the plunger to subject the plunger to the influence of the alternation of the magnetic field as the magnet structure is rotated 55 whereby the plunger is vibrated, said rotatable magnet structure being supported from the screen frame.

20 20. In combination, a screen frame, a screen carried by the frame, transverse frame 60 members carried from the screen frame above the screen, a plunger whose lower end is attached to the screen, guiding means for the plunger supported from the transverse members, a shaft rotatably supported from the 65 frame and carried above the transverse members, a magnet structure having alternate north and south poles and mounted on the shaft, in line with the free end of the plunger, and a solenoid coil to energize the 70 plunger.

21. In combination, a screen frame, a screen carried by the frame, transverse frame members carried from the screen frame above the screen, a plunger whose 75 lower end is attached to the screen, guiding means for the plunger supported from the transverse members, a shaft rotatably supported from the frame and carried above the transverse members, a magnet structure 80 having alternate north and south poles and mounted on the shaft, in line with the free end of the plunger, a solenoid coil to energize the plunger, means to limit the upward movement of the plunger, and a spring tending 85 to move the plunger downwardly.

EDWARD T. KEENAN.
